US0D1079618S

(12) **United States Design Patent** (10) **Patent No.:** **US D1,079,618 S**
(45) **Date of Patent:** **** Jun. 17, 2025**

(54) **CHARGING GUN**

(71) Applicant: **Guangdong Chongwei technology Co., LTD**, Yangjiang (CN)

(72) Inventor: **Caiyi Luo**, Yangchun (CN)

(73) Assignee: **Guangdong Chongwei technology Co., LTD**, Yangjiang (CN)

(**) Term: **15 Years**

(21) Appl. No.: **29/914,125**

(22) Filed: **Oct. 13, 2023**

(30) **Foreign Application Priority Data**

Jul. 28, 2023 (CN) 202330478520.3

(51) **LOC (15) Cl.** **13-02**

(52) **U.S. Cl.**

(57) **CLAIM**

The ornamental design for a charging gun, as shown and described.

DESCRIPTION

FIG. 1 is a front, left and top perspective view of a charging gun, showing my new design;

FIG. 2 is a rear, left and bottom perspective view thereof;

FIG. 3 is a front view thereof;

FIG. 4 is a rear view thereof;

FIG. 5 is a left side view thereof;

(Continued)

FIG. 6 is a right side view thereof;
 FIG. 7 is a top plan view thereof; and,
 FIG. 8 is a bottom plan view thereof.
 The broken lines shown in the drawings illustrate portions of the charging gun that form no part of the claimed design.

1 Claim, 8 Drawing Sheets
